US00D716284S

(12) **United States Design Patent**
Melanson et al.

(10) **Patent No.:** **US D716,284 S**
(45) **Date of Patent:** **** Oct. 28, 2014**

(54) **CASE FOR ELECTRONIC DEVICE**

(71) Applicants: **Christopher Melanson**, Fort Collins, CO (US); **Patrick Nelson**, Fort Collins, CO (US)

(72) Inventors: **Christopher Melanson**, Fort Collins, CO (US); **Patrick Nelson**, Fort Collins, CO (US)

(73) Assignee: **Otter Products, LLC**, Fort Collins, CO (US)

(**) Term: **14 Years**

(21) Appl. No.: **29/441,657**

(22) Filed: **Jan. 8, 2013**

(51) LOC (10) Cl. **14-03**

(52) U.S. Cl.

USPC **D14/250**

(58) **Field of Classification Search**

USPC ..... D14/138 AA, 138 AD, 138 C, 138 G, D14/203.3, 230, 238.1, 240, 247, 248, 250, D14/253, 341, 345, 346, 356, 439, 440, 447, D14/496; D13/103, 107, 119; D3/201, 218, D3/269, 273, 303; 206/37, 320; 455/456.1, 455/575.1, 575.4, 575.8

(57) **CLAIM**

The ornamental design for a case for electronic device, as shown and described.

DESCRIPTION

FIG. 1 is a first front isometric view of a case for electronic device showing our new design;

FIG. 2 is a front view thereof;

FIG. 3 is a second front isometric view thereof; and,

FIG. 4 is a rear isometric view.

The broken lines depict unclaimed environment. The broken lines form no part of the claimed design.

1 Claim, 4 Drawing Sheets

FIG. 1

FIG. 2

FIG. 3

FIG. 4
